UNITED STATES PATENT OFFICE.

WILLIAM S. TOTHILL, OF LOCKPORT, NEW YORK.

SHIRT.

1,111,626.

Specification of Letters Patent.

Patented Sept. 22, 1914.

Application filed January 5, 1910. Serial No. 536,533.

To all whom it may concern:

Be it known that I, WILLIAM S. TOTHILL, a citizen of the United States, residing at Lockport, in the county of Niagara and 5 State of New York, have invented a new and useful Improvement in Shirts, of which the following is a specification.

The object of this invention is to produce a neat appearing, dressy and comfortably fitting shirt which may be worn with or without a coat or waist-coat and in which the bosom or front of the shirt will retain its shape and position when being worn and will not buckle and wrinkle under the movements 15 of the wearer, thus preserving the neat appearance of the front of the shirt.

Shirts as commonly made, have long lower ends or tails intended to be tucked within the top of the trousers and when the wearer 20 sits down or bends forwardly the trousers cause the front of the shirt to buckle and wrinkle badly, as the trousers hold the shirt more or less from movement and prevent it from slipping downwardly within the trousers. This is particularly true in shirts having relatively long and stiff bosoms but also applies to plaited and soft bosom shirts. Further, the presence of suspenders upon 25 the outside of the shirt as they are generally worn detracts greatly from its appearance when no coat or waist-coat is worn, and when the shirt has a broad stiff bosom the suspenders interfere with the proper and easy set of the bosom and tend to crowd the 30 sides of the bosom together and cause it to bulge outwardly from the body of the wearer.

In the present invention the shirt is not provided with long lower ends or tails but is 40 made of such length as to extend only a short distance below the top of the trousers and has a straight finished lower end. The shirt is adapted to be worn outside of the suspenders and to hang downwardly from the shoulders of the wearer with its finished 45 lower end loosely surrounding the top of the trousers so that it is free to slip or move relative to the trousers and the body of the wearer. The suspenders are thus concealed 50 and do not interfere with the set of the bosom, nor with the free movement or slipping of the shirt up and down over the trousers. Its free lower end allows the shirt to retain its proper position irrespective of 55 the movements of the wearer and prevents

the bosom and front of the shirt from buckling and becoming wrinkled by reason thereof.

In the accompanying drawings: Figure 1 is a front elevation of a shirt embodying the 60 invention, showing the same worn with a coat. Fig. 2 is a similar view, partly in section, with the coat removed. Fig. 3 is a fragmentary front elevation of the shirt, 65 partly in section, showing the waist-band depending therefrom.

Like reference characters refer to like parts in the several figures.

As far as the present invention is concerned, the upper or body portion of the 70 shirt may be of any usual and suitable construction, being open in the front or back, or both, and having a stiff or soft front or bosom as may be desired.

In the construction shown, A represents 75 the body portion of a shirt of the open front, stiff bosom type having the usual sleeves a'a and open bosom a'. The shirt is made to fit the shoulders of the wearer and to hang downwardly therefrom outside of the suspenders. The body portion A is of sufficient length to extend a short distance below and outside of the top of the trousers and at its lower end is provided with a finishing band B which has its ends buttoned or otherwise suitably connected together at the 80 front of the shirt. The bosom a' extends downwardly at the front of the shirt to the band B. This band is preferably cut on a slight curve so that it flares downwardly 85 and outwardly somewhat when depending, and flares upwardly and outwardly when turned up, as shown in Figs. 2 and 3. It is starched or formed of some suitable material 90 so as to have a moderate degree of stiffness. After the shirt has been put on, this band B is turned inwardly and upwardly, loosely surrounding the upper portion of the trousers. This band is sufficiently stiff to retain 95 its upturned position and will tend to hold the lower end of the skirt slightly turned in to conceal the same and to give a neat and finished appearance thereto. After the band has been turned up and its ends fastened together it cannot fall down unless its ends 100 are unfastened, and no means for securing the band in its upturned position are therefore necessary. When the shirt has a long stiff bosom, the interlining is cut away at the folding line at the lower end of the 110

bosom, or this portion of the bosom is made of less thickness, to admit of its folding properly on the intended line.

The band is sufficiently loose around the upper portion of the trousers to enable it to slide over the same without binding, and the lower end of the shirt is thus free to move independently of the trousers in accordance with the movements of the wearer. This freedom of movement permits the bosom of the shirt to retain its shape and proper position without becoming buckled or wrinkled as in the case of a shirt which is tucked in and held by the trousers, or is otherwise held from movement at its lower end. The suspenders being inside of the shirt do not tend to crowd or press against the bosom or interfere with its retaining its proper position and have no tendency to hold the lower end of the shirt from free movement.

The shirt is made as described to enable it to be worn outside of the suspenders and trousers when no waist-coat is worn but its construction does not preclude it from being worn with its lower end tucked in the trousers in the usual manner when a waist-coat is worn. The shirt can thus be worn with or without a coat or waist-coat, as desired, and in either case presents a neat and attractive appearance. The body front of the

shirt can also, if desired, be made of any washable waist-coat material, thus producing a waist-coat effect.

I claim as my invention:

A tailless shirt which is cut to hang loosely from the shoulders and terminates at its lower end a short distance below the waist of the wearer where it is turned in and provided with an upturned finishing band which is comparatively stiff and which has overlapping ends adapted to be secured together, said band being cut on a curve to flare upwardly and outwardly when turned up and loosely surrounding the upper portion of the trousers of the wearer and holding said shirt outwardly away from said trousers so that said shirt can move independently of said trousers, the circumference of said band being approximately the same as that of the body of the shirt, whereby when the ends of the band are joined the shirt body will not be puckered, substantially as set forth.

Witness my hand, this 28th day of December, 1909.

WILLIAM S. TOTHILL.
